UNITED STATES PATENT OFFICE.

DANIEL B. KENNEY, OF HUNTINGTON, WEST VIRGINIA.

AUTOMOBILE-RADIATOR.

1,187,333.

Specification of Letters Patent. Patented June 13, 1916.

Application filed August 7, 1915. Serial No. 44,295.

To all whom it may concern:

Be it known that I, DANIEL B. KENNEY, a citizen of the United States, residing at Huntington, in the county of Cabell and State of West Virginia, have invented certain new and useful Improvements in Automobile-Radiators, of which the following is a specification.

My invention relates to improvements in radiators for automobiles or the like, adapted to receive as a heating medium, a portion of the exhaust from the internal combustion engine of the automobile, while not necessarily restricted to this use.

An important object of the invention is to provide a radiator of the above mentioned character, which is simple in construction, inexpensive to manufacture, strong, and durable.

A further object of the invention is to provide a radiator of the above mentioned character, the elements of which are secured to or carried by end members, which receive and take up all strains transmitted to the radiator and also preferably serve as means for attaching or anchoring the radiator in place.

A further object of the invention is to provide novel and simple means for connecting the radiator with the exhaust pipe of the engine.

Other objects and advantages of the invention will be apparent during the course of the following description.

In the accompanying drawings forming a part of this specification and in which like numerals are employed to designate like parts throughout the same, Figure 1 is a central vertical longitudinal sectional view through a radiator embodying the invention, Fig. 2 is a side elevation of the same, Fig. 3 is a side elevation of an automobile, having my radiators applied thereto, Fig. 4 is a side elevation of the connecting means or fitting between the radiator and the exhaust pipe of the engine. Fig. 5 is a detail section taken on line 5-5 of Fig. 4. Fig. 6 is a transverse sectional view taken on line 6-6 of Fig. 1, and, Fig. 7 is a horizontal sectional view taken on line 7-7 of Fig. 2.

In the drawings, wherein for the purpose of illustration is shown a preferred embodiment of my invention, the numeral 10 designates the body of an automobile, having a floor 11.

The numeral 12 designates an internal

combustion engine of the automobile, having an exhaust pipe 13, equipped with the usual muffler 14, as shown.

The numeral 15 designates my improved radiator, as a whole, comprising end attaching members or castings 16, provided at their lower ends with laterally or outwardly extending feet 17, preferably formed integral therewith. These feet are apertured, as shown at 18, for receiving screws 19 or the like, serving to attach the radiator to the floor or bottom of the automobile. These feet 17 may be disposed at a right angle to the attaching end members or castings, or at any other suitable angle with relation thereto, depending upon the inclination that it is desired to impart to the radiator. The attaching end members or castings 16 are provided upon their inner faces or sides with flanges 20, preferably formed integral therewith. Disposed within and near the lower ends of these flanges 20 are inner flanges 21, preferably formed integral with the end members or castings 16 and the flanges 20. The inner flanges 21 form with the upper portions of the flanges 20, interior recesses or chambers 22, adapted for the reception of packing 23, such as asbestos or the like, for a purpose to be described.

The numeral 24 designates a preferably imperforate inner casing or shell, preferably formed of sheet or metal. This inner casing has its opposite ends open and these ends are inserted within the chambers 22, to be securely held therein by the flanges 20 and 21. The ends of this inner casing 24 contact with the packing 23, which affords a gas tight union between such ends and the end members 16.

The numeral 25 designates a preferably perforated outer casing or shell, preferably formed of sheet metal. This outer casing has its ends formed open, and these open ends receive the outer flanges 20. These outer flanges are disposed slightly inwardly of the edges of the members or castings 16, providing shoulders 26, with which the ends of the casing 25 contact, to be flush therewith, as shown. The ends or castings 16 are preferably provided centrally thereof with openings 27, receiving a binding rod 28, having one end screw-threaded for receiving a nut 29. This binding rod also passes through the inner casing 24 and it serves to bind or lock the end members or castings 16 to the inner and outer casings.

but will permit of their separation, when desired.

The numeral 30 designates an inlet pipe, discharging into the interior of the inner casing 24 and connected therewith by means of a coupling 31. The interior of the inner casing 24 is also in communication with an outlet pipe 32, secured thereto by means of a coupling 33. This outlet pipe communicates with the atmosphere. As more clearly shown in Fig. 4, the pipe 30 is connected with a valve structure 34, the upper portion of which extends through an opening in the floor 11 of the automobile. This valve structure is opened and closed or adjusted by a hand wheel 35, arranged above the floor. The valve structure 34 is connected with a pipe 36, connected with a two-part tubular clamp, embodying co-acting members 37 and 38. These co-acting members are provided with flanges 39 for receiving bolts 40, which serve to connect them. The exhaust pipe 13 is provided adjacent each pipe 36 with an opening 41, for registration therewith. In use, the radiator is disposed in a convenient position within the automobile, upon its floor, as illustrated in Fig. 3. The screws 19 or the like serve to clamp the end members or castings 16 to the floor, whereby the radiator is held in place. The exhaust pipe 13 is connected with the pipe 30 by means of the two-part clamp and the opening 41 brought into registration with the interior of the pipe 36. If desired suitable packing may be arranged between the members 37 and 38 and the exhaust pipe. By proper manipulation of the hand wheel 35 the valve structure 34 will be adjusted to permit of the passage of a suitable amount of the heated gases or products of combustion through the radiator. These gases pass from the exhaust pipe 13, through opening 41, pipe 36, pipe 30, pipe 24, and through

pipe 32 to the atmosphere. It is obvious that the heat from these gases will radiate through the perforated outer shell 25.

It is to be understood that the form of my invention herewith shown and described is to be taken as a preferred example of the same, and that various changes in the shape, size, and arrangement of parts may be resorted to without departing from the spirit of the invention or the scope of the subjoined claim.

Having thus described the invention, I claim:

A radiator of the character described, comprising end members, each of which is provided near its lower end with an attaching foot, each end member being further provided upon its inner side with an outer continuous flange extending longitudinally thereof, and an inner flange connected with the outer continuous flange and spaced a substantial distance from the lower end of said continuous flange; an inner imperforate casing having its ends arranged within the upper portions of the continuous flanges and the inner flanges; an outer perforated casing receiving the continuous flanges in its ends whereby the bottom of the outer perforated casing is spaced a substantial distance from the bottom of the inner imperforate casing to provide an inclosed space; a rod extending through the inner imperforate casing and connecting the end members; pipes passing through the bottom of the outer perforated casing and leading into the inclosed space; and couplings arranged within the inclosed space and connecting the pipes with the inner imperforate casing.

In testimony whereof I affix my signature in presence of two witnesses.

DANIEL B. KENNEY.
